VARIABLE TRANSMISSION MECHANISM

Charles Walker, Knoxville, Tenn.

Application January 14, 1936, Serial No. 59,101

5 Claims. (Cl. 74—121)

My invention consists in new and useful improvements in a variable transmission mechanism particularly adapted for use in connection with registering devices of liquid dispensing pumps and the like, whereby the price per gallon, volume, and total cost of the liquid dispensed are indicated.

It is the primary object of my invention to provide a transmission mechanism of this type which will transmit the rotary movement of a driving member into a different rate of speed of a driven member, without in any way affecting the speed of rotation of said driving member.

Another object of my invention is to provide a mechanism of this character involving the principle of double eccentrics and sliding members for transmitting motion to a driven member.

A further object is to provide means for selectively positioning one eccentric with respect to the other to regulate the rate of speed of said driven member.

With the above and other objects in view which will appear as the description proceeds, my invention resides in the novel features herein set forth, illustrated in the accompanying drawings, and more particularly pointed out in the appended claims.

Referring to the drawings in which numerals of like character designate similar parts throughout the several views,

Fig. 1 is a view in front elevation, partly broken away, showing a liquid dispensing pump of the gasoline filling station type.

Fig. 2 is a sectional view taken on line 2—2 of Fig. 1.

Fig. 3 is an enlarged fragmentary sectional view taken on line 3—3 of Fig. 2.

Fig. 4 is a section taken on line 4—4 of Fig. 3.

Fig. 5 is an enlarged sectional view taken on line 5—5 of Fig. 2, and

Fig. 6 is a sectional view taken on line 6—6 of Fig. 5.

In the drawings, 1 represents the housing of a conventional gasoline dispensing pump in which are located a pump proper 2, connected by pipe 3 to a gasoline supply tank, not shown. An electric motor 4 suitably connected to the pump 2 by means of a belt or the like 5, operates the latter to force the gasoline up through pipe 6 into a meter 7 and out through discharge pipe 8 into the sight gauge 9 and connected discharge hose 10.

Upon the passage of fluid through the meter 7 from the inlet pipe 6 to the outlet line 8, a ver-

tical shaft 11 is rotated by means of suitable mechanism in the meter, the specific structure of which forms no part of my invention, the extent of rotation of said shaft 11 being commensurate with the volume of fluid being pumped. This shaft extends upwardly into operative connection with the transmission mechanism as will hereinafter appear.

Referring to Fig. 2, a series of registers A, B, and C for registering the price per gallon, the total cost of gasoline dispensed, and the total volume of gasoline dispensed, respectively, are mounted on a suitable shaft 12, a window W being provided in the front wall of the casing 1 immediately adjacent said registers as clearly shown in Fig. 1. These registers are of conventional structure, the register A being so arranged on shaft 12 that it will rotate with the latter, while dials B and C are freely mounted on the shaft.

A short shaft 13 (Fig. 4) is provided adjacent shaft 12 and projects outwardly through the casing 1, terminating in a crank handle H. Keyed to this shaft, I provide a suitable gear 14 adapted to mesh with a second gear A' keyed to shaft 12, whereby upon turning the handle H, the price register A will also be rotated to set the same as will hereinafter appear. The rotation of registers B and C which are freely rotatable on shaft 12, is effected by gears B' and C', respectively, connected to mechanism hereinafter described.

Gear A' on shaft 12 is also in mesh with a second gear 15 keyed to a shaft 16 suitably journaled at one end in one side of the casing 1 (Fig. 3). The other end of shaft 16 is threaded to engage a complementary threaded opening in a journal box 17 mounted thereon adjacent the gear 15, whereby upon rotation of the shaft 16, the journal box 17 will be moved longitudinally along said shaft as will later appear.

Referring to Fig. 2, the upper end of the shaft 11 is provided with a bevel gear 18 adapted to mesh with a second bevel gear 19 keyed to a longitudinally extending shaft 20, whereby rotation of the vertical shaft 11 will be transmitted to the shaft 20. One end of this shaft is mounted in a suitable bearing 21 in one side wall of the casing 1, the other end of the shaft terminating in a hollowed portion supported in a bearing 22 on a bracket 23 mounted within the casing 1. The hollowed portion of the shaft 20 is provided with a square opening adapted to receive the square end of a longitudinally movable shaft 20a as clearly shown in Fig. 6, whereby rotation

of the shaft 20 will also rotate shaft 20a. The other end of shaft 20a terminates in a circular disc 24 retained in a complementary opening in journal box 17 (Fig. 3).

5 Adjacent the bevel gear 19, I provide a gear 25 also keyed to shaft 20 and adapted to mesh with a complementary gear 26 mounted on a short shaft 27 supported by the bracket 23. Gear 26 is also in mesh with gear C' to rotate the 10 volume register C.

Mounted on the hollowed portion of shaft 20 adjacent its end, and freely rotatable thereon, I provide a flanged transmission gear 28 adapted to mesh with gear B' of the total cost register 15

15 B. As clearly shown in Fig. 6, the inner periphery of the flange is provided with two rows of teeth 29.

The mechanism for rotating the transmission gear 28 includes a stationary frame 30 suitably mounted on the casing 1 adjacent the gear 28 20 and lying in a plane parallel to the latter. 31 designates a second frame slidably mounted within a rectangular opening in frame 30, the upper and lower edges of frame 31 terminating in a rib or ridge 32 adapted to cooperate with corresponding grooves in the upper and lower edges of frame 30 adjacent said rectangular opening. As clearly shown in Fig. 5, the width of frame 31 is considerably less than the rectangular opening in frame 30, whereby said second frame is 30 longitudinally slidable within frame 30.

33 represents an auxiliary frame slidably mounted within a rectangular opening in frame 31, the vertical dimension of said auxiliary frame being substantially less than said rectangular opening in frame 31, whereby the former may be reciprocated vertically within frame 31. As in the case of frame 31, this auxiliary frame 33 also is provided with ribs or ridges along its vertical edges, adapted to cooperate with corresponding grooves along the inner edges of frame 31.

Frame 33 is provided with an enlarged central circular opening adapted to receive a crescent-shaped disc 35, the inner periphery of said 45 crescent disc slidably embracing a cam 36 provided on the outer end of the hollowed portion of shaft 20. Adjacent the inner periphery of disc 35, I provide a circular flange 37 having a series of teeth along its inner periphery to form 50 a spur gear 38 meshing with a small pinion 39 mounted on shaft 20a adjacent the cam 36.

The periphery of shaft 20a is spirally grooved longitudinally thereof, forming spiral threads adapted to cooperate with corresponding grooves 55 in the pinion 39, whereby upon the longitudinal movement of shaft 20a through the medium of crank H, gears A' and 15, threaded shaft 16 and journal box 17, pinion 39 will be rotated and in turn the disc 35 through the medium of its 60 spur gear 38.

Adjacent the pinion 39 and partly surrounding the latter, I provide a flange 40 in the form of an incomplete circle, integral with the shaft 20 on the hollowed end thereof, the open part of the 65 flange permitting the teeth on pinion 39 to mesh with the spur 38. The pinion 39 is retained in place on the shaft 20a adjacent the cam 36 by means of an annular disc 41 adapted to engage the outer face of the pinion. The annular disc 70 is suitably secured to the flange 40 by means of screws 42 engaging complementary threads in drilled openings on the outer edge of the flange as clearly shown in Fig. 6.

The inner face of the longitudinally sliding 75 frame 31 carries two parallel rack members 43

and 44 extending longitudinally from one side of said frame to the other and lying respectively above and below the hollowed portion of shaft 20 between the cam 36 and the closed face of the flange gear 28. The teeth on rack 43 are in mesh with a gear 45 mounted on one end of a hub 46 surrounding the shaft 20 adjacent the flanged gear 28, while the teeth on rack 44 are in mesh with a second gear 47 mounted on a hub 48 surrounding one end of hub 46. As clearly shown 10 in Fig. 6, the teeth on the racks 43 and 44 are oppositely disposed with respect to their longitudinal center to facilitate their meshing with the gears 45 and 47.

Each of the hubs 46 and 48 carries an upwardly extending arm 49 and 50, respectively, terminating adjacent the inner periphery of the flange 28. The upper extremity of arm 49 is provided with a pivoted pawl 51 in line for engagement with one row of teeth on the inner periphery of the flange 28, while arm 50 is also provided with a similarly pivoted pawl 52 for engaging the other row of teeth on the flange. These pawls 51 and 52 are similar in every respect, and as shown in Fig. 5, arm 49 and pawl 25 51 lie immediately back of arm 50 and pawl 52. As therein shown, a suitable spring 53 normally holds pawl 52 in engagement with the teeth on the flange 28, a similar spring (not shown) being provided on pawl 51.

It will thus be seen that with the pawls 51 and 52 pointing in the same direction, the longitudinal movement of frame 31 and supported racks 43 and 44, will rotate each of the gears 45 and 47 in opposite directions simultaneously, permitting 35 one of the pawls to engage its adjacent row of teeth on the flange to rotate the latter, while the other pawl slips freely over the other row of teeth.

Having described the construction of my improved device, its operation is as follows:

Assuming that the price per gallon of gasoline is twenty cents, and that the price dial A as seen in the window W indicates zero, the position of crescent disc 35 with respect to cam 45 36 will be concentric with shaft 20, thereby counterbalancing the throw of the cam. The handle H is then turned in a counterclockwise direction until the dials A register twenty. Simultaneously with the setting of this register, rotation of 50 the handle will rotate gear 15 keyed to shaft 16 in counterclockwise direction (Fig. 3), and by means of the screw threads on shaft 16 engaging complementary threads in the journal box 17, will cause the latter to move longitudinally away from gear 15. This will move the spirally grooved shaft 20a longitudinally into the hollowed square opening in shaft 20, and rotate pinion 39 in a counterclockwise direction. Rotation of this pinion will also rotate the crescent-shaped disc 35 in the same direction within the frame 33 through the medium of the flange 37 and spur gear 38, thus positioning the crescent disc about the cam 36 to regulate the relative position of the disc and frame 33 with 60 respect to the cam 36. The motor is then started to pump the gasoline through the meter 7, and as the liquid passes therethrough, shaft 11 will be rotated, in turn rotating shaft 20 through the medium of the bevel gears 18 and 19. Gear 25 keyed to shaft 20 will rotate therewith, and through the intermediate gear 26, will rotate gear C' to run up on the volume dial C the amount of gasoline being dispensed.

Cam 36 on shaft 20 will rotate with the latter, 75

together with the shaft 20a, and through the medium of its pinion 39 meshing with the spur 38, the crescent disc 35 will also rotate within the frame 33. Assuming that the relative positions of the crescent disc and cam are as illustrated in Fig. 5, the first half rotation of the shaft 20 will cause frame 31 to move longitudinally to the right and the frame 33 to slide vertically downwardly within the former. The longitudinal movement of frame 31 will transmit the same movement to the racks 43 and 44, and their engagement with the gears 45 and 47, respectively, will rotate the former in clockwise direction, and the latter in counterclockwise direction, permitting pawl 51 on arm 49 carried by the gear 45, to engage one row of teeth on the inner periphery of the flange 28 and rotating the latter in a clockwise direction, while pawl 52 will slip freely over the adjacent row of teeth 20 on said flange.

The continued rotation of the shaft 20 will move frame 33 upwardly, while frame 31 will be moved to the left, thus moving its racks 43 and 44 in the same direction, reversing the operation of the gears 45 and 47 above described, permitting pawl 52 to engage its adjacent row of teeth on the inner periphery of the flange 28, while allowing pawl 51 to slip over the adjacent row, yet rotating the flange 28 in the same clockwise direction.

Rotation of the flange 28 will also rotate gear B' meshing with the teeth on the outer periphery of the flange, and run up on the cost dial B, the total cost of the gasoline dispensed.

The above operation is repeated until the total amount of gasoline desired is dispensed, at which time the motor will be turned off to stop the rotation of shaft 11 and shaft 20 together with the transmission mechanism.

It will thus be observed that I have designed a rotary shaft having a cam, and that by providing a second eccentric about said cam, the degree of eccentricity of the latter can be varied from zero to its maximum, and that by mounting the cam within longitudinally and vertically sliding frames, the eccentric movement of the shaft is transmitted into reciprocating movement of the frames.

It will be further noted that by providing the frames with racks cooperating with suitable gears, the reciprocating movement of said frames will be transmitted into rotary movement of a driven element.

With this arrangement of eccentrics and sliding frames, I have provided a gasoline dispensing apparatus which is efficient in operation and which permits the transmission mechanism for operating the cost dial, to be regulated by simply turning the handle H to whatever price the gasoline is sold, which will selectively position the crescent disc 35 about the cam 36 to regulate the degree of eccentricity of the latter and in turn the extent of longitudinal movement of the frame 31 with its racks 43 and 44.

From the foregoing it is believed that the construction and advantages of my invention may be readily understood by those skilled in the art without further description, it being borne in mind that numerous changes may be made in the details disclosed without departing from the spirit of my invention as set out in the following claims.

I claim:

1. A variable transmission mechanism comprising a rotary shaft, means for driving said

shaft, a flanged transmission disc freely rotatable on said shaft, a series of teeth on the inner periphery of said flanged disc, a pinion freely mounted on said shaft, a radially extending arm carried by said pinion, a pawl member carried by said arm for engagement with said flange teeth, a slideable frame adjacent said disc, a rack carried by said frame in engagement with said pinion, eccentric means on said shaft for reciprocably sliding said frame and rack, and means for varying the extent of reciprocation of said frame and rack and in turn the rotation of said flanged disc.

2. A variable transmission mechanism comprising a rotary shaft, means for driving said shaft, a flanged transmission disc freely rotatable on said shaft, a series of teeth on the inner periphery of said flanged disc, at least two independent pinions freely mounted on said shaft, coaxial therewith, a radially extending arm carried by each of said pinions, pawl members carried by said arms for engagement with said flange teeth, a slideable frame adjacent said disc, a pair of oppositely disposed racks carried by said frame in engagement with the respective pinions for rotating each of said arms and in turn the transmission disc, eccentric means operated by the rotation of said shaft for reciprocably sliding said frame and racks, and means for regulating the extent of reciprocation of said frame and racks and in turn the rotation of said disc.

3. A variable transmission mechanism comprising a rotary shaft, means for driving said shaft, a flanged transmission disc freely rotatable on said shaft, a series of teeth on the inner periphery of said flanged disc, a pinion freely mounted on said shaft and coaxial therewith, a radially extending arm carried by said pinion, a pawl member carried by said arm for engagement with said flange teeth, a slideable frame adjacent said disc, a rack carried by said frame in engagement with said pinion, an auxiliary frame slideable within said first named frame in a direction perpendicular to the movement of the latter, eccentric means in engagement with said auxiliary frame and rotatable with said shaft for reciprocating said frame to operate said rack and in turn said arm and disc, and means for regulating the extent of reciprocation of said frames.

4. A variable transmission mechanism comprising a rotary shaft, means for driving said shaft, a flanged transmission disc freely rotatable on said shaft, a series of teeth on the inner periphery of said flanged disc, a pinion freely mounted on said shaft, a radially extending arm carried by said pinion, a pawl member carried by said arm for engagement with said flange teeth, a slideable frame adjacent said disc, a rack carried by said frame in engagement with said pinion, an auxiliary frame slideable within said first named frame in a direction perpendicular to the movement of the latter, a crescent-shaped member carried by said auxiliary frame, a cam member keyed to said shaft and embracing the inner periphery of said crescent-shaped member, and means for rotating said crescent-shaped member in said auxiliary frame to vary its relative position with respect to said cam and auxiliary frame, whereby said main frame and rack are given a reciprocating movement to rotate said arm and in turn said flanged disc.

5. A variable transmission mechanism comprising a rotary shaft, means for driving said shaft, a flanged transmission disc freely rotatable on said shaft, a series of teeth on the inner periphery

of said flanged disc, a pair of independent pinions freely mounted on said shaft and coaxial therewith, a radially extending arm carried by each of said pinions, pawl members carried by said arms 5 for engagement with said flange teeth, a slideable frame adjacent said disc, a pair of oppositely disposed racks carried by said frame in engagement with the respective pinions, an auxiliary frame slideable within said first named frame in a 10 direction perpendicular to the movement of the latter, a crescent-shaped member carried by said

auxiliary frame, a cam member keyed to said shaft and embracing the inner periphery of said crescent-shaped member, and means for rotating said crescent-shaped member in said auxiliary frame to vary its relative position with respect to said cam and auxiliary frame, whereby said main frame and racks are given a reciprocating movement to rotate said arms and in turn said flanged disc. 5

CHARLES WALKER. 10
